UNITED STATES PATENT OFFICE.

JACOB SCHINNELLER, OF PITTSBURG, PENNSYLVANIA.

PROCESS OF BURNING HYDROCARBONS.

SPECIFICATION forming part of Letters Patent No. 417,342, dated December 17, 1889.

Application filed December 19, 1888. Serial No. 294,072. (No model.)

To all whom it may concern:

Be it known that I, JACOB SCHINNELLER, a resident of Pittsburgh, in the county of Allegheny and State of Pennsylvania, have invented a new and useful Improvement in the Process of Burning Hydrocarbons; and I do hereby declare the following to be a full, clear, and exact description thereof.

My invention relates to the burning of oil and like light hydrocarbons in metallurgical and other furnaces, its object being to so intermingle the oil-vapor and air and to heat the same before combustion that a practically perfect combustion of the said hydrocarbons is obtained in the furnace.

To these ends my invention consists, generally stated, in dropping the oil upon a body or mass of heated balls or lumps of refractory material and drawing air through said refractory material and so intermingling the oil-vapor and air and burning it under said mass of refractory material.

It also consists, in connection with the same process, in bringing the said balls or blocks of refractory material exposed to the heat at the delivery end of said mass to the entrance end thereof, upon which the oil is dropped, whereby the heat of the mass of refractory material is maintained and the oil can be vaporized practically as soon as it comes in contact with said refractory material.

To enable others skilled in the art to practice my invention, I will describe the same more fully, referring to the accompanying drawings, in which—

Figure 1 is a longitudinal section of the most approved form of furnace employed in carrying out the same. Fig. 2 is a rear view thereof. Fig. 3 is a cross-section on the line xx , Fig. 1; and Figs. 4 and 5 show other forms of furnace suitable for the purpose.

Like letters of reference indicate like parts in each.

In the construction of apparatus best suited for practicing my said invention, as illustrated in Figs. 1, 2, and 3, it is shown as applied to a puddling or heating furnace a , said furnace having the stack or chimney b , which leads to such a height or through such a length of flue (when a single chimney is employed for a number of furnaces) that a continual draft can be maintained through the furnace, and in that way the oil-vapor and air

can be drawn into the entrance end thereof, so as to be burned at the entrance end of and 55 within the furnace-chamber. The entrance end of the furnace is formed of a series of combustion-flues c , which extend longitudinally of the furnace and communicate with the chamber a' , these flues being formed of 60 brick or tile and having at the end thereof an air-blast inlet d , which, in the construction preferred, extends the entire length of the said series of combustion-flues c , and is controlled by a suitable valve d' , so as to 65 regulate the amount of air fed to said combustion-flues. Extending above said combustion-flues c is the casing e , which is preferably lined with fire-brick, so forming a chamber f , which is open at the upper or entrance and lower or delivery ends thereof, and is filled with a mass composed of balls, blocks, or lumps of fire-brick or other refractory material, the preferred form used being a series of balls of fire-brick within said chamber f , as shown at g . I prefer to employ these refractory balls for the reason that they provide for the change in the position of the balls without great labor, as by opening the lower part of the chamber f the balls can 70 be withdrawn therefrom, said chamber having the outlet-port f' , which is closed by a block or blocks f^2 , and said opening being in line with the platform i , so that when said blocks f^2 are withdrawn the balls can roll 75 through said port f' onto the platform and can be shoveled in the open upper end of the chamber f , provision being thus made for the changing of the position of the balls and the bringing of the balls exposed to the high heat 80 generated in the combustion-flues to the upper or entrance end of the chamber f . Arranged above the upper open end of the chamber f is the oil-supply pipe h , controlled by a suitable valve h^2 . This pipe h has suitable 85 perforations or openings therein, which permit of the dropping or spraying of the oil directly upon the said fire-balls, so that the oil dropping or being sprayed upon the upper end of said body of refractory material will 90 pass between the several balls and descend through the chamber f , the oil coating to some extent the different balls, and also being vaporized by the heat thereof, so that the draft from the stack b through the furnace a and 95 combustion-flue c will draw this oil-vapor 100

through the refractory material in said chamber *f* and thence into the combustion-chamber. As the upper end of the chamber *f* is open, the air will be drawn in through said opening, thus providing part of the air necessary for combustion, and part of the air will be supplied by the air-inlet *d* communicating with the combustion-flues. In order, however, to provide for the regulation of the supply of air to and the proper intermingling thereof with the oil-vapor, I have formed along the sides of the chamber *f* a series of flues *m*, which extend through the brick-work of said chamber and communicate with the valves *k*, said valves being mounted in suitable seats in the casing *e*, which is provided with suitable bearings for the same. The said valves *k* are preferably horizontal valves, having at each end seats or journals, and at certain points therein enlarged cylindrical portions to hold them in line and prevent the warping thereof under the high heat, and between said bearings and said enlarged portions the valves being formed flat, as shown at *l*—that is, of such shape that when turned in one position they close the openings or inlets entirely, and when turned at right angles thereto leave the inlets practically open—the valve being adjusted to any position between these two, according to the amount of air to be fed to the oil-vapors in the chamber *f*. The said valves have the angular ends *k'*, by which they can be turned and adjusted as desired. As the oil-supply pipe *h*, especially the part thereof having the perforations therein, is liable to become gummed or filled with the thicker or heavier portion of the oil, and there is therefore liability of the perforations being stopped or clogged, I arrange within this portion of the pipe containing said perforations the spiral cleaner or scraper *n*, which corresponds in diameter to the internal diameter of the pipe, and has a handle *n'* extending through a stuffing-box at the end of the pipe, thus providing for the turning of the scraper *n* within the pipe and the freeing or loosening of any gummy matter therein. In order to further provide for the removal of such materials, I also connect with said pipe *h* a steam-pipe *p*, which will furnish steam to said pipe and assist in the vaporization of said heavy gummy material and the driving of the same out of the pipe, so that I am enabled to maintain the pipe in proper condition for work, and to give a free escape to said pipe *h* when it is cleaned the end *h*³ thereof is formed open and provided with a valve *h*⁴, which may be opened during the cleaning operation.

In employing my invention with the said form of apparatus it may be applied, as before stated, to any suitable furnace, whether for metallurgic, boiler, or other heating purposes, and the oil or other like light hydrocarbons are forced under pressure either from an accumulator or by gravity from a tank and dropped or sprayed through the perfora-

tions of the pipe *h* upon the fire-clay balls *g* contained in the chamber *f*, and said oil continues to percolate downwardly through the opening or interstices between the balls or blocks until it reaches the combustion-flues *c*, when, with the air fed to said flues or entering through the several valves or openings in the chamber *f*, a proper mixture for forming combustion is obtained, and by the ignition of the same in the said flues the oil-vapor is burned, the combustion being supported by the air intermingled therewith, the products of combustion passing through the chamber *a'*, and thence upwardly through the stack *b*, and this being continued until a positive draft is obtained through the stack and the lower part of the mass of fire-clay balls is raised to a high heat, when the oil is vaporized by said heated refractory balls, and it is intermingled in the interstices between the balls with the air entering through said valves or inlets, so that when the furnace is all ready for proper practical work a proper intermingling of the oil-vapor and the air to form combustion in the flues is obtained. The burning of the oil-vapor in said flues heats the whole mass of fire-clay balls, but especially heats the lower part thereof, and, as it is desired to maintain said mass of refractory balls at a high heat, at intervals during the burning of said materials, by opening the ports *f'*, the fire-clay balls may be withdrawn from the lower part of the said chamber and these highly-heated balls be introduced in the upper part of the same, as above described, so that the oil will drop directly upon the highly-heated balls and be vaporized as soon as it enters the chamber and a more proper mixing of the oil for combustion be thus obtained, the mass of balls being not only held at a high heat, but at the same time the balls upon which the oil drops and upon which the heavier particles of the hydrocarbon settle are thus brought to the lower part of the chamber *f*, where they are directly exposed to the high heat generated in the combustion-flues, and any such settlement of tar or other heavy hydrocarbon thereon can be burned from the same and utilized for maintaining combustion in the furnace.

During the operation of the furnace the several valves *d'* or *k* may be regulated in such way as to provide for the proper mixing of the air and oil-vapors and the burning of the same in the combustion-flues, and a proper regulation for such vapors can be obtained according as a carbonizing, decarbonizing, or neutral flame is desired. In case the oil-supply pipe *h* should become clogged, as above described, all that is necessary is to turn the spiral cleaner *n* within the same, which will free practically all the gummy mass from contact with the pipe and the openings therein, and, in case it is necessary to discharge such heavy or gummy materials, by opening the valve *h*⁴, closing the valve *h*², and opening the valve of the steam-pipe *p*,

such materials will be vaporized and the pipe cleaned by the steam.

In Fig. 4 I have shown another form of apparatus suitable for practicing my invention, which is practically the same as that shown in Figs. 1, 2, and 3, except that the casing *e* containing the balls or blocks of refractory material is mounted on suitable journals, the point of journaling said casing being indicated by dotted lines, as at *r*, and said casing, which is suitably lined, has formed therein the chamber *f*, having communicating therewith the air-inlets *m*, controlled by the valves *k*, as above described. Said casing is arranged to be turned on said journals so as to bring the mass of refractory material in the lower part thereof, and which has been highly heated by direct contact with the flame and heat generated in the combustion-flue *c*, to the upper end of said chamber, upon which the oil is dropped, and in this way to provide for the vaporization of the oil as soon as it comes in contact with said refractory material. At the same time, by bringing the refractory material which was in the upper end of said chamber to the lower end thereof, I am enabled to reheat the same and to carry the material upon which any coating of heavy hydrocarbon has been deposited directly into contact with the high heat of the combustion-chamber, so that any such deposit will be burned from the refractory material and all the carbon or hydrocarbons therein consumed. In order to hold the mass of fire-clay balls or lumps within said chamber *f*, where it is arranged as shown in Fig. 4, I employ what might be termed a "fire-clay grating," as shown at *s*—that is to say, I close the ends of the chamber by means of an open-work grating of proper material to stand the heat and at the same time to confine the mass of material within said chamber. Such grating may be formed of a series of fire-clay balls, which are cast together and united, leaving suitable openings for the passage of the air and oil-vapors through the same; or it may be formed of checker-work or any such like proper construction which will provide within the chamber for the passage of the oil-vapors from the upper to the lower end thereof and the mixing or intermingling of the air therewith during the time that the oil-vapors or the oil in a liquid state, if it has not been vaporized, shall be passing through the interstices or openings between the balls, lumps, or blocks of refractory material.

The operation of this apparatus in practicing my invention is practically the same as described in connection with the other figures, differing only in that, instead of withdrawing part of the refractory material at the lower end and introducing it at the upper end of the said chamber, in order to bring the material exposed to the heat at such lower or delivery end to the entrance end of the chamber, the casing is simply rotated on its axis or journal and the heated balls or blocks at

the lower end brought to the upper end thereof, so that the oil can drop directly upon said oil-heated blocks, and the said chamber *f* is rotated at intervals, according as found best for the proper vaporization and combustion of the oil.

In Fig. 5 is shown another form of furnace suitable for practicing my invention, in which the combustion-flues *c* are formed of the mass of fire-clay balls or lumps. Said mass of balls extend down so as to fill a pocket *t*, forming the lower part of the chamber *f*, and the initial combustion is formed within said mass, the complete combustion being obtained in the furnace-chamber *a'*. To change the position of the balls, ports in the side walls, as shown in dotted lines, are formed in the part of the pocket *t* nearest the furnace-chamber *a'*, and the heated balls can be withdrawn through these ports and introduced at the entrance end of the chamber *f*.

By my invention I am enabled to provide for the proper vaporization of the oil as it comes directly from the tank or accumulator, the intermingling of the air in proper quantities to support combustion therewith, and the regulating of the combustion from said intermingled oil-vapor and air, and this without the employment of steam for vaporization purposes, and by means of a simple apparatus which can be operated by unskilled labor, occupies practically no room, and can be constructed at a low cost.

No claim is made herein for the apparatus described in this specification, that forming the subject-matter of a separate application filed April 19, 1889, Serial No. 307,665.

What I claim as my invention, and desire to secure by Letters Patent, is—

1. The herein-described process of burning oil or other hydrocarbons, consisting in dropping the oil upon a mass of heated balls or lumps of refractory material and drawing air through said refractory material, so intermingling the oil-vapor and air and passing the same from and burning it at the lower or delivery end of said mass, substantially as and for the purposes set forth. 115

2. The herein-described process of burning oil or other hydrocarbons, consisting in dropping the oil upon a mass of heated balls or lumps of refractory material and drawing air through said refractory material, so intermingling the oil-vapor and air and burning the same at the lower or delivery end of said mass, and at intervals bringing the refractory materials exposed to the heat at the delivery end of said mass to the entrance end 125 thereof, upon which the oil is dropped, substantially as and for the purposes set forth.

In testimony whereof I, the said JACOB SCHINNELLER, have hereunto set my hand.

JACOB SCHINNELLER.
